(57) **CLAIM**

The ornamental design for a portable jewelry bag, as shown and described.

DESCRIPTION

FIG. 1 is a top, front, right side perspective view of a portable jewelry bag showing my new design;
FIG. 2 is a bottom, rear, left side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an alternative perspective view of the portable jewelry bag when in an open state.
The dotted broken lines shown on the portable jewelry bag depict stitching that form no part of the claimed design.

1 Claim, 9 Drawing Sheets
